UNITED STATES PATENT OFFICE.

SAMUEL S. CORNELIUS, OF CORINTH, MISSISSIPPI.

CROSS-ARM FOR ELECTRIC OR SIGNAL WIRES.

1,181,066.

Specification of Letters Patent. Patented Apr. 25, 1916.

Application filed February 9, 1915. Serial No. 7,213.

To all whom it may concern:

Be it known that I, SAMUEL S. CORNELIUS, a citizen of the United States, residing at Corinth, in the county of Alcorn and State of Mississippi, have invented new and useful Improvements in Cross-Arms for Electric or Signal Wires, of which the following is a specification.

The invention relates to a cross arm for electric or signal wiring, and is especially adapted for use on posts or poles.

The primary object of the invention is the provision of a cross arm wherein the construction thereof serves to shed water, sleet or snow from the insulators, to which are adapted to be connected the electric wires, for protection to said insulators.

Another object of the invention is the provision of a cross arm wherein the construction thereof prevents the decay or rotting of the same resultant from moisture penetrating the arm through apertures or openings therein.

A further object of the invention is the provision of a cross arm wherein the bracket and insulators can be fastened thereto so that such fasteners will be protected during inclement weather, thereby assuring increased life to the cross arm with maximum service.

A still further object of the invention is the provision of a cross arm which is simple in construction, novel in form, strong, durable, reliable and efficient in use, and inexpensive in manufacture and installation.

With these and other objects in view, the invention consists in the construction, combination and arrangement of parts as will be hereinafter fully described, illustrated in the accompanying drawing, and pointed out in the claims hereunto appended.

In the drawing: Figure 1 is a fragmentary side view of a telegraph pole or post showing the cross arm in end elevation constructed in accordance with the invention applied thereto. Fig. 2 is a front elevation. Fig. 3 is a top plan view. Fig. 4 is a sectional view on the line 4—4 of Fig. 2. Fig. 5 is a sectional view on the line 5—5 of Fig. 3.

Similar reference characters indicate corresponding parts throughout the several views in the drawing.

Referring to the drawing in detail, A

designates a portion of a pole or post, and B 55 the cross arm connected thereto and constructed in a manner hereinafter fully described. The cross arm B comprises a body 5 which can be of any suitable length and thickness, and constructed from any preferred material, wood being well adapted for ordinary purposes. The body 5 is formed with a rounded upper surface 6, and a concaved or inset bottom surface 7, the marginal edge 8 about the bottom surface 7 being designed to serve as a skirt to protect and shield insulators fastened to the said bottom surface of the arm, the insulators being hereinafter fully described. Secured to the pole or post A is a bracket 10 70 formed with an offset portion 11 and a fork 12, the arms of which are fixed to the bottom face 7 of the cross arm B, and in this manner the said cross arm is secured in spaced relation to the pole or post, and is 75 held rigid thereon.

At suitable points on the bottom face 7 of the cross arm B are adapted to be mounted insulators, each comprising an inwardly tapered conical-shaped member 13, preferably made from porcelain, glass or other insulating material, the smaller end being next to the bottom face 7, while the wider end is dished at 14 to receive a washer 5 through which is centrally passed a screw 85 fastener 16 which mounts the insulator on the bottom face 7 of the cross arm, the electric wire being fastened to the insulator in any suitable manner. Connected to the arm B and to the post A are suitable braces 17 to 90 hold the same rigid.

From the foregoing description, taken in connection with the accompanying drawing, it is thought that the construction of the device will be clearly understood, and therefore a more extended explanation has been omitted.

What is claimed is:—

1. A cross arm of the class described having a rounded top throughout its length, 100 and an inset opposite lower face forming a marginal flange about the latter providing an unbroken skirt, and a bracket connected to the inset bottom face and adapted to fasten the cross arm to a support.
2. A cross arm of the class described having a rounded top throughout its length, an inset opposite lower face forming a mar-

ginal flange about the latter providing an unbroken skirt, a bracket connected to the inset bottom face and adapted to fasten the cross arm to a support, and an insulator 5 mounted on the bottom face and having a fastener extending only partially through the body.

In testimony whereof I affix my signature in presence of two witnesses.

SAMUEL S. CORNELIUS.
